UNITED STATES PATENT OFFICE.

ALBERT C. GRUNWALD, OF CHICAGO, ILLINOIS, ASSIGNOR TO PRECISION METAL WORKERS, OF CHICAGO, ILLINOIS, A CORPORATION OF ILLINOIS.

OIL-CUP.

1,380,059.

Specification of Letters Patent. Patented May 31, 1921.

Application filed August 8, 1919. Serial No. 316,173.

To all whom it may concern:

Be it known that I, ALBERT C. GRUNWALD, a citizen of the United States, residing at Chicago, in the county of Cook and State of Illinois, have invented a new and useful Improvement in Oil-Cups, of which the following is a specification.

This invention relates particularly to oil-cups adapted to be applied to bearings where it is not convenient to employ forced feed. The primary object is to provide an oil-cup which will serve to gradually feed the oil to the bearing; which may be readily re-filled, and which is adapted to effectively exclude dust and grit.

The invention is illustrated in its preferred embodiment in the accompanying drawing, in which—

Figure 1 represents an elevational view of the improved oil-cup; Fig. 2, a plan view of the same, in closed condition; Fig. 3, a plan view of the same in open condition; Fig. 4, a longitudinal sectional view, taken as indicated at line 4 of Fig. 1; Fig. 5, a broken sectional view, taken as indicated at line 5 of Fig. 1; and Fig. 6, a plan view of the wick device employed.

In the construction illustrated, A represents a cup, or elongated tubular member, which is provided at one end with a threaded nipple A', and which is equipped at the opposite end with a cap A²; and B represents a wick device which is securely mounted in the nipple-end of the cup.

The tubular body A and nipple A' are preferably formed integrally by drawing a steel disk into cup form, the bottom portion of the cup being contracted to form the nipple, and perforated to provide a passage for the wick. The base-portion of the cup A is contracted in diameter, as indicated at 1, to form a seat or chamber for the head-portion of the wick device. The nipple A' is of still smaller diameter, thus forming a seat for the head-portion of the device B.

The wick device B preferably comprises a small cup-shaped member 2, the bottom of which is formed with a perforate neck 2^a; a body, or bundle, of fibrous wick material 3 which extends through the nipple A' and into the small cup 2; and a small perforate disk 4 which fits into the cup 2 and is secured therein by an inwardly-spun flange, or bead, 2^b, with which the small cup 2 is provided. The cup 2 may be stamped or

drawn from sheet-metal. The wick may comprise one or more lengths of loosely twisted heavy cotton or yarn cord. If desired, these lengths may be formed into loops and the loop ends forced through the neck-portion 2^a of the cup 2 from above; the fibers of the extremities of the cords may then be spread out to fill the cup 2, and the disk 4 may be pressed into the cup and the edge-portion of the cup spun or pressed over the disk to hold it in position. If desired, the loop ends of the cords projecting below the lower or free end of the nipple may be trimmed off. The disk 4 is provided with a series of small perforations 4^a, which will allow the oil contained in the chamber A to seep through into the small cup 2 and thoroughly saturate the wick, which will conduct the oil to the bearing. The small cup 2 conforms accurately to the housing provided therefor at the base-portion of the cup A and is forced into position, so that the oil cannot leak past the cup 2, but must pass through the wick.

The cap A² preferably is stamped from a disk of sheet-metal. It is provided with a flange 5 and may be secured on the cup A by forcing the cap under considerable pressure onto the cup. A tight driving fit is thus obtained, which provides an oil-tight joint. Nevertheless, the cap may be forced off, in case it be desired to replace the wick device. The cap is provided at some distance from its center with a perforation 6 through which oil may be introduced into the cup. The cap is also equipped with a segmental closure 7 which is pivotally connected with the central portion of the cap B² by means of a rivet 8. The segment 7 is desirably in the form of a segment of a cap which surmounts the cap A² and conforms thereto. It has at the apex a pivotal ear 7^a through which the rivet 8 extends. It also has a depending flange 7^b which embraces the flange 5 of the cap A², and the lower portion of this flange is turned inwardly to provide a lip 7^c which engages the lower edge of the flange 5. The flange 7^b is provided with an outwardly-struck circumferential embossment 7^d, which contains a leaf-spring 7^e which bears against the flange 5 and produces such frictional engagement therewith as to prevent the possibility of accidental moving of the closure. The rivet 8 also holds the closure closely against the cap and is adapted to create a

certain amount of friction. The end-portions of the segmental flange 7^b are extended somewhat beyond the body of the segment and curled outwardly and back upon the 5 flange 7^b, thus producing smooth projections, or thumb-pieces, 7^e, which serve as a means for opening and closing the closure.

The cap A² is equipped on its upper surface with small studs, or stops, 9 and 10, 10 which limit the movement of the closure in the closing and opening operations, respectively. These stops may be provided by punching the metal of the cap outwardly.

It will be noted that the construction of 15 the segment 7 is such as to provide its flange with sharp edges 7^b. When the segment is swung on its swivel, it scrapes the outer surface of the cap A² clean throughout the arc of movement. Such a close fit is secured by 20 the construction employed as to effectively exclude all dust and grit from the oil-cup.

The improved oil-cup is shaped for use 25 in connection with the bearings of stationary engines, in connection with the bearings for springs of automobiles, and in various other situations. The improved device is exceedingly simple in construction, capable of being manufactured at moderate cost, and is thoroughly effective for its purpose.

30 The cup may be made of convenient size to properly lubricate an ordinary bearing for a period of several weeks, without the necessity of re-filling the cup in the meantime.

35 The foregoing detailed description has been given for clearness of understanding only and no unnecessary limitation should be understood therefrom, but the appended

claims should be construed as broadly as permissible, in view of the prior art. 40

What I regard as new and desire to secure by Letters Patent is:

1. A device of the character set forth, comprising an oil-cup provided at one end with a tubular nipple, and a wick device 45 comprising a small cup pressed into the base-portion of the oil-cup and a wick having a portion confined in said small cup and a portion extending into the nipple, said small cup having a perforate wall for feeding oil gradually from the oil-cup to the wick.

2. A device of the character set forth, comprising an oil-cup having a contracted base-portion and a still further contracted 55 portion affording a tubular nipple and affording also a seat, and a wick device comprising a hollow member forced into position against said seat and a wick having a portion confined in said hollow member and 60 a portion extending into the nipple, said hollow member having a perforate wall affording a bottom for the oil-cup and through which the oil may seep gradually to the wick. 65

3. A device of the character set forth, comprising an oil-cup having a contracted base-portion and a still further contracted portion affording a tubular nipple and affording also a seat, and a wick device comprising 70 a cup-shaped member forced into position against said seat, wick material in said cup-shaped member, and a perforate plate in said cup-shaped member above said wick material.

ALBERT C. GRUNWALD.
